(57) **CLAIM**

The ornamental design for a bicycle stand, as shown and described.

DESCRIPTION

FIG. 1 is a perspective view of a bicycle stand according to the claimed design.

FIG. 2 is a front view of the bicycle stand.

FIG. 3 is a rear view of the bicycle stand.

FIG. 4 is a right side view of the bicycle stand.

FIG. 5 is a left side view of the bicycle stand.

FIG. 6 is a top view of the bicycle stand.

FIG. 7 is a bottom view of the bicycle stand; and,

FIG. 8 is a perspective view of the bicycle stand in an extended configuration.

The broken lines in the drawings illustrate portions of the bicycle stand that form no part of the claimed design.

1 Claim, 5 Drawing Sheets
